ATTORNEYS.

UNITED STATES PATENT OFFICE.

FRANK M. SAYFORD, OF BROOKLYN, NEW YORK.

STENCIL-CARD AND METHOD OF STENCILING MONOGRAMS.

1,351,068.

Specification of Letters Patent. Patented Aug. 31, 1920.

Application filed December 18, 1919. Serial No. 345,752.

To all whom it may concern:

Be it known that I, FRANK M. SAYFORD, a citizen of the United States, residing at Brooklyn, county of Kings, State of New York, have invented a new and useful Stencil-Card and Methods of Stenciling Monograms, of which the following is a specification.

My present invention comprehends a novel construction and arrangement of stencil card which is especially designed for stenciling monograms and also comprehends a novel method of stenciling monograms.

10 The stencil cards may have any desired contour and it will be apparent that the formation of the letters of the alphabet as well as the general shape of the monogram may vary indefinitely in practice.

20 In accordance with my present invention, I employ on each stencil card a plurality of the same letters of the alphabet and for purposes of illustration, I have shown typical stencil cards having three representations of the same letter of the alphabet each representation being different from the other in accordance with the position which such letter is to assume in the finished monogram.

30 My invention further comprehends a novel method of making monograms which consists in stenciling the first letter of the monogram by employing the first letter of the stencil card, then stenciling the second letter of the monogram by employing the second letter of the requisite stencil card and progressively employing a letter of the stencil which corresponds to the order in which such letter is to be placed on the monogram.

Other novel features of construction and advantage will hereinafter more fully appear in the detailed description.

For the purpose of illustrating my invention, I have shown in the accompanying drawings a typical embodiment thereof which is at present preferred by me, since said embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figures 1, 2 and 3 represent, respectively, plan views of stencil cards embodying my invention and by means of which my novel method may be carried out.

35 Figs. 4, 5 and 6 represent, respectively, different monograms which have been formed on the stencil cards seen in Figs. 1, 2 and 3.

Similar numerals of reference indicate 40 corresponding parts in the figures.

Referring to the drawings,

I have deemed it necessary to illustrate in the present instance but three stencil cards which I have identified by reference 45 characters 1, 2 and 3, respectively, the stencil card 1 having represented thereon a plurality of formations of the letter A, the stencil card 2 having represented thereon a plurality of different formations of the 50 letter B and the stencil card 3 having represented thereon a plurality of different formations of the letter C. It will be understood from this that a stencil card for each letter of the alphabet is employed and on 55 each stencil card a plurality of different formations of the same letter are employed in accordance with the order in which they are to appear in the finished monogram.

60 In order that the different stencil cards 60 may be brought into accurate register with the monogram which is being made each stencil card is provided with the apertures 4 and 5, respectively, the location of which may vary as is apparent and equivalent 65 means may be employed as is apparent for recording the proper register of the stencil card while the monogram is being made.

On the stencil card 1 is represented a 70 monogram formed of the letter A, a left- 75 hand letter A being represented at 6, a middle letter A being represented as indicated at 7 and a right-hand letter A being represented as at 8.

75 The stencil card 2 has represented thereon 80 the letter B, the left-hand letter B being indicated by the reference character 9, the intermediate or second letter B being indicated by the reference character 10 and the right-hand letter B being indicated by the 85 reference character 11.

85 The stencil card 3 indicative of the letter C has in a similar manner represented thereon the left-hand letter C as indicated at 12, the intermediate letter C as indicated at 13 90 and the right-hand letter C as indicated at 14.

Assuming now that it is desired to form the monogram A, B and C, as indicated in Fig. 4, the stencil card 1 is placed in position and the first letter A of the monogram is formed by utilizing the A of card 1 which is the letter A indicated by reference character 6. As the second letter of the monogram is to be the letter B, the second letter B of the stencil card 2 is employed, as indicated by reference character 10, and the stencil card 2 is placed in register with the position which the first stencil card occupies and the second letter of the monogram is then made.

15. The next letter of the monogram is the letter C which is the third or right-hand letter of the monogram so that it is necessary to employ the third letter C of the stencil card 3 which is indicated by the reference character 14.

If the monogram is to be, for example, the letters B, C, A, as shown in Fig. 5, the first letter employed in the monogram would be the left-hand B, as indicated by 9 on the 25 stencil card 2. The second letter would be the letter C, indicated by reference character 13 on the stencil card 3 and the third letter would be the letter A, indicated by reference character 8 on the stencil card 1.

20. If the monogram C, A, B is to be formed, as shown in Fig. 6, it will be apparent from the foregoing that I employ the C indicated by reference character 12 on the stencil card 3, the letter A indicated by the reference character 7 on the stencil card 1 and the letter B is indicated by reference character 11 on the stencil card 2.

It will be clear from the foregoing that the order in which a letter on a stencil card 40 is used depends upon the order in which it appears in the monogram. The stencil cards may be made with two or more representations of the same letter in the form of a monogram but for purposes of illustration, I have preferred to show each stencil card as having three representations of the same letter.

It will further be apparent that the general form of the monogram as an entirety or the formation or appearance of the letter on a stencil card may vary widely in practice and I do not therefore desire to be limited to any special design of monogram or any special design of letters. It will be 55 apparent that if a person desires to form a monogram in the manner herein disclosed all that it is necessary for him to do is to purchase three stencil cards indicative of the letters which form his monogram and then

form the monogram by stenciling in the 60 manner herein set forth.

The letters in the stencil card can be formed by apertures, slots or any other desired or conventional manner.

The letters on each stencil card form a monogram and a letter is represented on each stencil card in the position in which it will appear in any selection or order in the finished monogram.

It will now be apparent that I have devised a new and useful stencil card and method of stenciling monograms which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent is:

1. A stencil comprising a card having a plurality of forms of the same letter of the alphabet thereon arranged in the form of a monogram.

2. A stencil comprising a card having a plurality of forms of the same letter of the alphabet thereon arranged in the form of a monogram, each letter varying in design in accordance with the order in which it is arranged in the monogram.

3. The method of stenciling with stencils each having a plurality of forms of the same letter thereon arranged in the form of a monogram, which consists in progressively 100 stenciling each letter of the monogram from a different stencil using the letter on each stencil corresponding to the position which such letter is to assume in the monogram.

4. A stencil for stenciling monograms, comprising a card having a plurality of forms of the same letter of the alphabet thereon arranged in the form of a monogram, said card being provided with means whereby different cards with different letters thereon can be brought into registration with the monogram which is being made.

FRANK M. SAYFORD.
